United States Patent Office

Des. 178,561
Patented Aug. 14, 1956

178,561

BOTTLE

Ray J. Wunderly, Glenshaw, Pa., assignor to National Cordial Company, Chicago, Ill., a corporation of Illinois

Application November 22, 1954, Serial No. 33,174

Term of patent 3½ years

(Cl. D58—7)

I claim:

The ornamental design for a bottle, as shown.
